UNITED STATES PATENT OFFICE.

ALBERT ANTHONY RUPPERT, OF DETROIT, MICHIGAN, ASSIGNOR TO GENERAL MOTORS CORPORATION, OF DETROIT, MICHIGAN, A CORPORATION OF DELAWARE.

TRIMMING.

Application filed September 11, 1926. Serial No. 134,765.

This invention relates to the trimming and upholstering of automobile bodies, and particularly automobile doors.

The prevailing trimming material for closed automobile bodies is broadcloth, velour, mohair and plush. It is customary to use a heavy cardboard, strawboard or fibre board backing for the trimming material that is used on the door, as ordinarily the door well is open between the lock board and the bottom rail of the door.

Heretofore it has been customary to nail this trimming together with the backing to which the trimming is glued to the door by means of substantially headless brads. These brads are nailed right through the pile and then an awl or hooked instrument is taken and the outer ply of the trimming is pulled over the end of the brad so that the brads are concealed. However, it is still possible to the eye of a close observer to see where the brads have been pulled through the material. This is especially true where the higher grade material known as broadcloth is used, as this material has no pile and the holes made by the brads will be apparent unless some kind of gimp or binding is used to cover up the holes. Furthermore, the brads are practically headless and it will be apparent that the trimming can be easily pulled off and very often does come off the brad.

It is the object of the present invention to provide a trimming nailing strip which not only entirely eliminates the pulling of the material over the end of the brads, but also greatly strengthens the engagement between the door stile and further reinforces the edge of the fibre or strawboard underneath.

Referring to the drawings:

Fig. 1 is a perspective of an automobile door equipped with the new type of trimming strip.

Fig. 2 is a fragmentary perspective of a door stile showing the trimming and the strip in position.

Fig. 3 is a fragmentary cross section of the trimming before it is applied to the door.

Fig. 4 is a fragmentary sectional perspective of the strip itself.

Fig. 5 is a similar view of a modified form.

The strip is a sheet metal strip which can be made in continuous lengths on machines for rolling or drawing metal chan-

nels. Primarily it is a metal channel strip forming the channel *a*, which receives the reinforcing board of fibre board, strawboard, or cardboard, which is designated *b*. The trimming material *c*, which may be velour, broadcloth, plush or any other suitable material is glued around the strip after the channel has received the edge of the board reinforcement. This channel strip is preferably doubled to two-ply thickness on the side *d*, and the tacks *e* are clamped in between the plies of the double thickness by means of the two plies engaging the head of the tack. This is shown in Fig. 3.

However, a single channel strip may be used as shown in Fig. 5, and in place of the clamping tack heads by means of a double ply arrangement, these heads may be spot-welded in place. It will readily be seen that the channel strip may be fitted over the edge of the reinforcing board, the trimming turned over the channel strip and glue the channel strip on the board. The trimming may then be easily nailed to the door stile lock board or any other adjacent wooden part in a way that it will be little likely to come off.

The pulling of the trimming off the brad heads is entirely eliminated as an operation, and furthermore the holes in the cloth are entirely eliminated where they would be especially objectionable in broadcloth and other plain fabrics.

What I claim is:

1. A nailing strip for trimming material, comprising a continuous channel strip with a channel opening arranged to fit over the reinforcing board for the trimming and receive the folded trimming on the outside of the channel, said channel having affixed to one side thereof a plurality of nailing members so that when the channel, the reinforcing board strip and the trimming are fitted together the same may be nailed to the support with the nailing devices completely concealed.

2. A nailing strip for trimming material, comprising a sheet metal channel strip having a double ply at one side of the channel and tacks having their heads secured between the two plies and projecting right angularly from the side of the channel, the opening in the channel arranged to fit over the edge of the reinforcing board while the trimming fits around the outside of the chan-

nel and the whole trimming assembly being securable to the underlying support by driving the nails into the support.

3. A trimming unit for automobile bodies, comprising a reinforcing board, a metal strip carrying nails on one side secured to the reinforcing board, and a trimming cloth folded around the edge of the reinforcing board and the nailing strip, the whole se-
curable as a unit to the underlying support by driving the nails thereinto.

4. A trimming for automobile bodies, com-

prising a reinforcing board, a metal channel strip fitting around the edge of the board and carrying nails on the inner wall of the channel, and trimming material fitting around the channel strip and the board, the whole unit being securable to the underlying support.

In testimony whereof I have affixed my signature.

ALBERT ANTHONY RUPPERT.
